UNITED STATES PATENT OFFICE.

WILLIAM E. ADAMS, OF SALEM, AND WILLIAM J. MURRAY, OF BEVERLY,
MASSACHUSETTS.

OILING DEVICE FOR GASOLENE-ENGINES.

1,015,466.

Specification of Letters Patent.

Patented Jan. 23, 1912.

Application filed October 11, 1907. Serial No. 396,873.

To all whom it may concern:

Be it known that we, WILLIAM E. ADAMS and WILLIAM J. MURRAY, citizens of the United States, residing at Salem and Beverly, respectively, in the county of Essex and State of Massachusetts, have invented certain new and useful Improvements in Oiling Devices for Gasolene-Engines; and we do hereby declare the following to be a full, clear, and exact description of the invention, such as will enable others skilled in the art to which it appertains to make and use the same.

The present invention relates to an improved oiling apparatus, and is designed primarily for use in connection with hydro-carbon motors, although in its broader aspects it is also capable of use with other forms of apparatus.

20 The object of the present invention is to provide an oiling apparatus by which a definite amount of oil can be supplied at regular intervals and in a certain and reliable manner to parts of machinery which are difficult of access, and more particularly whereby the cylinder walls and piston of hydro-carbon motors or similarly constructed apparatus can be supplied with oil in a satisfactory manner.

30 With the above object in view the present invention broadly considered contemplates the provision of an oiling device so located with relation to the part to be oiled as to be separated therefrom by an intervening space and means whereby the oiling device is caused to operate in timed relation to the moving parts which are to be oiled, to intermittently throw a jet of oil upon said parts.

40 As applied to a hydro-carbon motor or similar apparatus provided with an open ended cylinder and a piston working therein, the invention contemplates the provision of an oiling device located at a suitable distance from the cylinder, and means for operating the oiling device in timed relation to the movements of the piston to intermittently throw a jet of oil into the open end of the cylinder.

In the preferred form of the invention 50 the oiling device is extremely simple in construction and comprises an oil receptacle located beneath the open end of a cylinder, and means operating intermittently in timed relation to the piston to cause a jet of oil 55 to escape from the receptacle into the open end of the cylinder. As applied to a multiple cylinder motor the invention contemplates the provision of an oil receptacle extending beneath the open ends of all of the 60 cylinders, and means whereby jets of oil are caused to escape from the oil receptacle into each cylinder as the piston in each cylinder reaches the desired position. In the best 65 form of the invention which has yet been devised, and which is hereinafter specifically described, the oil receptacle consists of a hollow shaft located in the lower part of the crank casing of a multiple cylinder motor, and passing through a stationary 70 sleeve or bushing beneath each cylinder, means being provided for rotating the shaft in timed relation to the movements of the crank shaft and pistons, and suitably located openings being provided in the shaft and 75 bushings which during the revolution of the shaft come into register and thereby allow jets of oil to escape from the hollow shaft upwardly into the open ends of the cylinders.

80 The present invention will be clearly understood from an inspection of the accompanying drawings in which—

Figure 1 is a view in side elevation partly in section of a four-cylinder hydro-carbon 85 motor embodying the several features thereof in their preferred form, and Fig. 2 is a cross sectional view taken on a plane passing through one of the cylinders.

The motor illustrated in the drawings is 90 of well-known construction and need not be specifically described, 1 indicating the cylinders, 2 to the pistons working therein, 3 the crank shaft connected by the piston rods 4 to the pistons, and 5 the crank casing, 95 which as usual is a tight casing and completely incloses the crank shaft.

The improved oiling apparatus illustrated

in the drawings comprises an oil receptacle in the form of a hollow shaft 6, which is located in the lower part of the crank casing directly beneath the crank shaft, and is mounted to rotate in suitable bearings. This shaft is rotated at one-half the speed of the crank shaft by means of a sprocket chain 7 passing over sprocket wheels secured to the shafts. Directly beneath each cylinder the shaft passes through a stationary sleeve or bushing 8 and through stuffing boxes 9 at each end of the sleeve. Each sleeve is provided with three holes as indicated at 10, 11 and 12 in Fig. 2, and the shaft 6 is provided with holes which, as the shaft revolves, register successively with the holes 10, 11 and 12. One of these holes is indicated at 13. The holes 10, 11 and 12 are so arranged that during the rotation of the shaft 6 three jets of oil are allowed to escape successively from the shaft, one jet being thrown directly upward against the end of the piston rod when it is in its lowest position, and the other jets being thrown obliquely upward against opposite sides of the cylinder walls. The holes 13 in the shaft 6 are so arranged, and the shaft is rotated in such timed relation with the crank shaft that a jet of oil is thrown upwardly into the open end of a cylinder at times when the crank pin is out of the path of the jet, one jet, for instance, being thrown upwardly into the open end of the cylinder when a crank pin is in the position illustrated in Fig. 2, and the other jet being thrown upwardly into the open end of the cylinder when the crank pin is in a diametrically opposite position.

The requisite amount of oil is supplied to the shaft 6 under pressure by means of a suitable pump indicated at 14, which is actuated from the crank shaft by means of a belt 15 passing over pulleys secured to the crank shaft and to the shaft of the pump. The pump takes its oil from a reservoir 16 through a pipe 17, and delivers the oil to the shaft 6 through a pipe 18 and stuffing box 19 at one end of the shaft the pipe 18 being so connected to the shaft 6 as to permit the rotation of the latter. To maintain the oil in the shaft 6 at a constant pressure a by-pass is provided by means of a pipe 20 leading from the pipe 18 to a return pipe 21, and this by-pass is provided with a pressure regulating valve indicated at 22. The surplus oil which collects in the lower portion of the crank casing is returned to the reservoir 16 by means of return pipes 21, and the reservoir is provided with a suitable strainer 23 for the returned oil.

By means of the apparatus above described, a definite, predetermined amount

of oil is supplied with certainty and at the desired times to the walls of the cylinders, and the cylinders and pistons are lubricated in a satisfactory manner without any liability of either too little or too much oil being supplied thereto.

The nature and scope of the present invention having been indicated, and the preferred form of the invention having been described, what is claimed is:

1. The combination with an open-ended cylinder and a piston working therein, of an oil receptacle provided with an oil discharge orifice, said orifice being located at all times without the cylinder, means for supplying oil to said receptacle under pressure and means operating in timed relation to the movement of the piston to permit a jet of oil to escape intermittently from said orifice into the open end of the cylinder, substantially as described.

2. The combination with an open ended cylinder and a piston working therein, of a hollow shaft located beyond the open end of the cylinder, a sleeve through which the shaft passes, means for rotating the shaft in timed relation to the movement of the piston, and means for supplying oil to the shaft under pressure, said sleeve and shaft being provided with holes arranged to register and permit a jet of oil to escape into the open end of the cylinder, substantially as described.

3. The combination with a plurality of cylinders and pistons working therein, an oil receptacle extending across the open ends of said cylinders, means for supplying oil thereto under pressure, and means operating in timed relation to the movement of the pistons to cause jets of oil to escape intermittently from said receptacle into the open ends of the cylinders, substantially as described.

4. The combination with the cylinders, pistons, crank shaft and crank casing of a multiple cylinder motor, of a hollow shaft within the casing extending across the open ends of the cylinders, a sleeve beneath each cylinder through which the hollow shaft passes, means for supplying the hollow shaft with oil under pressure, and means for rotating the hollow shaft in timed relation to the movements of the pistons, said hollow shaft and sleeves being provided with holes arranged to register and permit jets of oil to be thrown into the open ends of the cylinders, substantially as described.

5. The combination with the parts of the apparatus to be oiled, of an oil receptacle provided with a discharge orifice, said orifice being located in fixed position and separated from the parts to be oiled by an intervening space, means for creating pressure

on the oil, means for controlling the discharge of oil from the orifice and across the space on to the parts to be oiled and mechanism for actuating the said means to cause 5 the intermittent discharge of oil from said orifice at predetermined times to the parts of the apparatus to be oiled, substantially as described.

In testimony whereof we affix our signatures, in presence of two witnesses.

WILLIAM E. ADAMS.
WILLIAM J. MURRAY.
